Primary Examiner — Karen E Kearney(74) *Attorney, Agent, or Firm* — Perkins Coie LLP(57) **CLAIM**

The ornamental design for a housing for a network device, as shown and described.

DESCRIPTION

FIG. 1 is a top, side perspective view of an embodiment of a housing for a network device showing our new design in a first configuration.

FIG. 2 is a top plan view of the housing shown in FIG. 1.

FIG. 3 is a bottom plan view of the housing shown in FIG. 1.

FIG. 4 is a first side view of the housing shown in FIG. 1, the opposite side being a mirror image thereof.

FIG. 5 is a front view of the housing shown in FIG. 1, the back being a mirror image thereof.

FIG. 6 is a top, side perspective view of the housing shown in FIG. 1 in a second configuration.

FIG. 7 is a top, side perspective view of the housing shown in FIG. 6 in the context of additional environment showing a network device positioned within the housing and the housing connected to a T-bar of a suspended ceiling; and,

FIG. 8 is a top, side perspective view of the housing shown in FIG. 1 in the context of additional environment with the housing connected to a mounting plate.

The details shown in broken lines illustrate portions of the housing for a network device that form no part of the claimed design.
